UNITED STATES PATENT OFFICE.

CULLEN B. SNELL, OF BROOKLINE, MASSACHUSETTS.

WINDING-MACHINE.

1,084,371.

Specification of Letters Patent.

Patented Jan. 13, 1914.

Application filed February 3, 1913. Serial No. 745,946.

To all whom it may concern:

Be it known that I, CULLEN B. SNELL, a citizen of the United States, residing at Brookline, in the county of Norfolk, State 5 of Massachusetts, have invented a certain new and useful Improvement in Winding-Machines, of which the following is a specification, reference being had therein to the accompanying drawings.

10 The machine in which the invention resides is particularly applicable for winding coils for electrical purposes, although I contemplate its employment in winding for other purposes also. It is contrived to wind 15 a continuous wire or other material of like form in flat spiral layers, one against another, such layers being alternately increasing spirals and decreasing spirals, the former being wound from the center outward, and the latter wound from the outer periphery inward.

My machine is characterized by the employment therein of a presser-means which acts in axial direction against one end of the 25 mass being wound, and of a winding-guide located intermediate the said presser-means and the said end and traversed outward and inward between them to lay the wire or other material in increasing and decreasing spirals 30 successively, the said presser-means conforming to the winding-guide by developing a progressive clearance-wave at the said guide, and acting to hold in place the portion of wire that has just been laid by the said 35 guide. In a convenient mode of embodiment of the main principles of the invention the presser and mass being wound rotate in unison and the winding-guide is non-rotating.

40 An embodiment of the invention is illustrated in the drawings, in which latter—

Figure 1 shows in side elevation, partly broken away, a machine containing the said embodiment. Fig. 1^a is a partly-sectional detail view on enlarged scale, showing the upper portion of a shell or bobbin, and the pressure-device acting thereon. Fig. 2 is a plan of the said machine, in section on line 2, 2, of Fig. 1. Fig. 3 is a view partly in section on line 3, 3, of Fig. 2. Fig. 4 is a view similar to Fig. 3, but with the rotary cylinder in vertical section. Fig. 5 is a plan view of the rotary cylinder and segmental pressers. Fig. 6 is a side view and Fig. 7 a top view of the central arbor. Figs. 8, 9 and 50 10 are detail views showing one of the seg-

mental pressers. Fig. 11 is a side elevation and Fig. 12 a sectional view of a shell or bobbin.

Having reference to the drawings, the latter represent a machine constructed to wind upon a shell or bobbin such as that shown separately in Figs. 11 and 12, and comprising a cylindrical barrel 1 having an external flange or collar 1^a adjacent one end thereof. Such end is represented in Figs. 1^a and 12 as closed, and as formed interiorly with a recess 1^b located off-center to receive a driving projection on the rotating arbor 2 (Figs. 1^a, 2, 4, 6 and 7) of the machine. The coil is wound upon the said barrel, with the first or endmost spiral against the said collar or flange, as in Figs. 1 and 3. For a portion of its length the arbor 2 is cylindrical, to fit the interior of the barrel of the shell or bobbin. The driving projection is marked 2^a in Figs. 6 and 7.

The arbor 2 is rotated through combining it with a cylinder 3 having suitable actuating connections by means of which it is rotated. Such connections comprise herein a helical gear 4 fixed upon an extension 3^a of said cylinder, and a like gear 4^a fixed upon driving shaft 5 and meshing with gear 4. The arbor is located at the center of an axial opening within said cylinder, as shown more particularly in Figs. 3 and 4, the lower portion, 2^b, of the arbor being fitted to an eye 3^b, Fig. 5, at the lower end of the extension 3^a of the cylinder. Said portion 2^b is squared, and so is the said eye, so that the arbor is compelled to turn in unison with the cylinder. This construction provides a sliding connection between the arbor and the cylinder that permits the arbor to be shifted in the direction of its length, axially of the cylinder, without interfering with the driving connection between cylinder and arbor.

Means is provided for pressing the arbor with yielding force upward through the cylinder, to maintain its driving projection 2^a in driving engagement with the shell or bobbin; that is to say, to keep such projection within the recess 1^b at all times, whether the shell or bobbin be in its lowest, an intermediate, or its highest position. In the present instance this means comprises an expanding spiral spring 6 which is mainly contained within a longitudinal bore of the arbor and rests by its lower end upon the bottom of a yoke 7 attached to the lower end

of the cylinder. This end of said spring surrounds a steadyng-pin 8 that is attached to the said bottom and extends up part-way into the said bore. The spring supports the 5 arbor and also tends to raise the same. An elongated foot 2^a on the lower end of the arbor fits between the opposite sides of the yoke, and through engagement therewith assists in causing the arbor to rotate in unison with the cylinder. When an empty shell 10 or bobbin is placed upon the arbor and pressed down within the cylinder as in Figs. 1, 3, 4, depressing the arbor as in such figures, the spring is thereby compressed. As 15 the shell or bobbin gradually is raised during the winding process by the growing length of coil wound thereon the spring by expanding causes the arbor to follow upward so as to keep its driving projection 2^a within 20 the recess 1^b of the shell or bobbin.

I provide convenient means for pressing the shell or bobbin downward with yielding force so as to keep the wound portion of the coil thereon in a state of compression and 25 cause the convolutions of each succeeding spiral to be wound under pressure between the preceding spiral and an opposing surface. Such pressure - means comprises in this instance an upright rod 9, Figs. 1 and 3, 30 fitted to fixed guides 10, 10, Fig. 1, through which it is capable of vertical sliding movement, and splined to such guides to prevent it from rotating, the said rod carrying a weight 11, Fig. 1, and its lower end having 35 applied thereto a shoe 12, Figs. 1, 1^a, and 3, which rests upon the top end of the shell or bobbin. The said shoe comprises a cap 12^a, Fig. 1^a, receiving the lower end of the rod, a flanged disk 12^b which makes contact with 40 the top end of the shell or bobbin, and ball-bearings 12^c, 12^c, between said cup and flanged disk permitting the flanged disk to turn freely in unison with the shell or bobbin relative to the rod 9.

45 A winding-guide is shown at 13, Figs. 1 and 2. Its end, provided with a delivery eye or passage for the wire or other material, *a*, coming from a source of supply *b*, shown as a filled spool, extends above the 50 upper end of the rotary cylinder 3 into proximity to the periphery of the cylindrical portion 1 of the shell or bobbin upon which the winding is to be effected. The said guide is carried by a bar 14 working in 55 fixed guides 15, 15, and is given a gradual traversing movement outward from and inward toward the axis of the arbor 2 by means of a heart-cam 16 engaging with a roll 14^a carried by said bar, and a contract- 60 ing spiral spring 17 acting with a tendency to move the bar in opposition to the cam. The said cam 16 is fixed upon an upright shaft 18, and is rotated by means of driving connections comprising a worm-gear 19 65 fixed upon the said upright shaft, and a

worm 20 fixed upon the shaft 5. On the way from the source of supply to the winding-guide, the wire passes through a supplemental guide-loop 14^a which also is carried by bar 14.

70 As will be appreciated, it is considerable of a problem to wind fine wire or other material of like form in successive flat spirals, one against another, alternately increasing and decreasing, upon an arbor, shell or bobbin, especially when employing a non-rotating winding-guide, and depending upon the rotation of the said arbor, shell or bobbin to draw the wire or the like from the source of supply. The problem is especially trying 80 in the case of winding a decreasing flat spiral, *i. e.*, one in which the convolutions are wound one within another from the outer periphery to the inner periphery. To accomplish such work I apply pressure to 85 the wire or other material immediately upon its being laid in forming a convolution, and maintain pressure upon the convolutions of the spiral which is being wound, holding them thereby between the collar or 90 flange of the arbor, shell, or bobbin and an opposing surface, or between the convolutions of the last preceding spiral and such surface. The preferred type of means for doing this is shown in the drawings. 21, 21, 95 etc., Figs. 3, 4, 5 and 8, 9, 10, are segmental pressers, forming a circular series. They are mounted upon cylinder 3 so as to rotate in unison therewith and with the arbor 2 and shell or bobbin. Their body-portions 100 21^a, Fig. 8, work in longitudinal grooves in the periphery of cylinder 3, in which they are capable of movement lengthwise of the axis of the cylinder and arbor. To give them such movement, the said bodies are 105 notched on their outer edges at 21^b, Figs. 8 and 9, to fit a stationary cam-ring 22, Figs. 3 and 4, which is fixed by means of pins 23, 23, in the fixed box or casing 24 surrounding the body of the cylinder. The working portions of the segmental pressers fit together in the form of a ring which closely surrounds the cylinder of the shell or bobbin. The diameter of such ring exceeds that of the coil to be wound. The cam-path of the 115 cam-ring 22 is all on one level except at the point immediately in line with the winding-guide, and immediately adjoining such point at front and rear. Here, there is a bend in the cam-path sufficient to cause the 120 working portion of each presser in turn to clear the winding-guide in arriving at and passing such guide. Fig. 3 illustrates this.

125 In operation, as the arbor and shell or bobbin rotate, the delivery-portion of the winding-guide works out and in between the shoulder or flange 1^a and the ring of segmental pressers, the said shoulder or flange being forced toward the said pressers by the action of weight 11. Thereby, in beginning 130

the winding operation, the wire is wound in spiral form between the said shoulder or flange and the said ring of segmental pressers, an increasing spiral being wound as the 5 guide moves gradually outward, and a decreasing spiral between such increasing spiral and the said ring as the guide moves inward again. As each presser in succession arrives in close proximity to the guide 10 it is withdrawn downward as in Fig. 3 so as to clear the guide, but immediately after passing the guide is restored to working position again so that the portion of wire just laid by the guide is clamped against the 15 preceding spiral, in the place in which it was laid in the convolution being formed, and the different convolutions of the spiral that is being wound are held clamped against the preceding spiral all the way 20 around except immediately at the guide.

Preferably, I employ a continuous flat ring 25 of flexible material which intervenes between the ring of segmental pressers and the wound spirals, to give a continuous contact surface. This ring may be composed of 25 rubber, or equivalent material to serve as a cushion which contributes to preventing displacement of the convolutions. I have employed rubber in practice, and I have also 30 employed a ring of parchmentized paper. The winding-guide passes between the wound spirals and this ring, which latter is depressed by the guide in passing the latter, as in Fig. 3, and then recovers its normal 35 straight condition. As each spiral in succession is wound in between the preceding spiral and the ring of segmental pressers of the said flexible ring, it forces the shell or bobbin upward against the resistance of the 40 weighted pressure rod 9.

The amount of the weight 11 determines the density of the coil lengthwise.

The ring 25 may be left temporarily upon the barrel 1, at the end of the coil, when the 45 coil has been wound to the required length and the filled shell or bobbin is removed from the machine, to hold the final spirals in place until the second head or flange is applied to the said barrel, and removed at the 50 time of applying said second head or flange, or it may be permitted to remain permanently.

It will be perceived that the cam-ring 22 acts to depress certain of the segmental 55 pressers downward in a curve at the winding-guide, to clear the latter, and as the cylinder revolves carrying the segmental pressers successively to and past the winding-guide the successive pressers are depressed one after another progressively. The 60 action is that of a wave by which the segmental pressers are in turn caused to clear the winding-guide in passing the same. A similar progressive wave is produced in the 65 flexible ring 25 by the winding-guide, the

portion of such ring which at any given instant is in contact with the winding guide being pressed down by the latter, and being pressed up again against the adjacent convolutions, immediately after passing the 70 winding-guide, by the action of the segmental pressers in being actuated by the cam-ring. The ring 25 may take the form of a cushion of suitable thickness, in which case the segmental pressers and their cam 75 may be dispensed with.

In case the exterior diameters of different shells or bobbins, or other receivers, should vary or be irregular, the ring 25, by fitting closely by its inner periphery against the exterior of a shell, bobbin or other receiver, 80 will prevent the inner convolutions of the wire or other material being wound from dropping between the said exterior and the inner edges of the presser-segments.

The tops or working ends of the segments 85 constitute a pressing surface. The ring 25 may in some instances be attached to the working ends of the presser-segments as by means of cement or pins, or otherwise; and, as will be obvious, the said ring 25 may be divided up into segments of a size corresponding with the working ends of the presser-segments, in case continuity in the 90 surface contacting with the spirals and convolutions being wound is not deemed essential.

The invention is not restricted in the application of the principles thereof to the precise construction and arrangement herein 100 shown and described.

While a machine embodying the principles of my invention as hereinbefore described is particularly adapted for the winding of wire or other material in a dry state 105 or with a non-adhesive surface, it is equally available for use in the winding of material (either covered or uncovered) which is coated, preferably just prior to being deposited as a convolution of the coil in process of formation, with a substance or compound, which may be either of semi-liquid and of an adhesive nature, or ordinarily solid but more or less completely liquefied or melted before application to the material. In such case, as 110 the material is wound in position the coating compound serves not only to cement or secure the material in the position in which it is deposited, but also, where said compound is of a dielectric nature and is applied to insulated wire, it may serve to more perfectly 115 insulate the convolutions of wire from those lying adjacent to the same. An arrangement for coating of the material in process of winding may be easily applied, by one 120 familiar in the art, to my invention as above described. Figs. 1 and 2 show one such arrangement, where the material is arranged to pass, preferably just before entering the 125 guiding loop 14^a of the bar 14, through a 130

trough *c* containing the coating substance or compound in a softened or liquefied condition. In said trough *c* is a roll *d* under which such material is drawn during its passage through the trough *c* and by which it is submerged in the coating material contained in the said trough.

What is claimed is,—

1. In a machine for winding in spiral layers, one against another, in combination, a presser which acts in axial direction against one end of the mass being wound, and which progressively conforms to the winding-guide and holds in place the portion of material that has just been laid by the said guide, and a winding-guide which traverses outward and inward between the presser and the said end of the wound mass to lay the material in increasing and decreasing spirals successively.
2. In a machine for winding in spiral layers, one against another, in combination, a presser which rotates in unison with the mass being wound, acting in axial direction against one end of such mass, and which conforms to the winding-guide and holds in place the portion of material that has just been laid by the said guide, and a non-rotating winding-guide which traverses outward and inward between the presser and the wound mass to lay the material in increasing and decreasing spirals successively at said end of such mass.
3. A machine for winding in spiral layers, one against another, comprising in combination, a winding-guide, means for producing relative rotation between the mass being wound and the winding-guide, means for traversing the winding-guide outward and inward to deliver the material in increasing and decreasing spirals successively, and presser-means between which and the preceding wound spiral the winding-guide works, said presser-means receding from the said spiral in a progressive clearance-wave at the winding-guide and immediately assuming position to hold in place the portion of material which has just been delivered by said winding-guide.
4. In a winding machine, in combination, a winding-guide, means for producing relative rotation between a receiver on which winding is effected and the said winding-guide, means for traversing the winding-guide outward and inward to deliver the wire or other material in increasing and decreasing spirals successively, and presser-means between which and the preceding spiral the winding-guide enters and works, said presser-means progressively conforming to the winding-guide to clear the latter and immediately assuming position to hold in place the portion of wire which has just been laid.
5. In a winding machine, in combination,

a winding-guide, means for producing relative rotation between the mass being wound and the said winding-guide, means for traversing the winding-guide outward and inward to deliver the wire or other material in increasing and decreasing spirals successively, and a presser comprising a series of presser-segments between which and the preceding spiral the winding-guide delivers the wire or other material, said presser-segments receding in a wave at the winding-guide to clear the latter and immediately assuming position to hold in place the portion of wire which has just been laid.

6. In a winding machine, in combination, a non-rotating winding-guide, means for rotating the mass which is being wound, means for traversing the winding-guide outward and inward to deliver the wire or other material in increasing and decreasing flat spirals successively, and presser-means between which and the preceding spiral the winding-guide enters and works, said presser-means progressively receding from said spiral at the winding-guide to give clearance to the latter and immediately resuming position to hold in place the portion of material that has just been laid by the guide.

7. In a machine for winding in spiral layers, one against another, in combination, a presser comprising a series of presser-segments which rotates in unison with the mass being wound, acting in axial direction against one end of such mass, and which conforms to the winding-guide, said presser-segments acting successively to hold in place the portion of wire or other material that has just been laid by the said guide, and a non-rotating winding-guide which traverses outward and inward between the presser and the wound mass to lay the wire or other material in increasing and decreasing spirals successively at said end of the mass.

8. In a winding machine, in combination, a non-rotating winding-guide, means for rotating the mass which is being wound, means for traversing the winding-guide outward and inward to deliver the wire or other material in increasing and decreasing flat spirals successively, and a series of segmental pressers between which and the preceding spiral the winding-guide delivers the wire or other material, said series receding in a wave at the winding-guide and immediately resuming position to hold in place the portion of material which has just been laid.

9. In a winding machine, in combination, a winding-guide, means for producing relative rotation between the mass being wound and the said winding-guide, means for traversing the winding-guide outward and inward to deliver the wire or other material in increasing and decreasing spirals successively, presser-means between which and the preceding spiral the winding-guide de-

livers the wire or other material in being wound, and a cam by which said presser-means is caused to form a clearance-wave at the winding-guide and immediately assume 5 working position to hold the adjacent convolutions in place.

10. In a winding machine, in combination, a non-rotating winding-guide, means for rotating the mass which is being wound, means 10 for traversing the winding-guide outward and inward to deliver the wire or other material in increasing and decreasing flat spirals successively, presser-means between which and the preceding spiral the winding-guide 15 delivers the wire or other material in being wound, and a cam by which said presser-means is caused to form a clearance-wave at the winding-guide and immediately resume working position to hold in place the 20 portion of material that has just been laid.

11. In a winding machine, in combination, a winding-guide, means for producing relative rotation between the mass being wound and the said winding-guide, means for traversing the winding-guide outward and inward to deliver the wire or other material in increasing or decreasing spirals successively, a series of segmental pressers between which and the preceding spiral the winding-guide 25 30 delivers the wire or other material, and a cam producing a clearance-wave in said series at the winding-guide.

12. In a winding machine, in combination, a non-rotating winding-guide, means for rotating the mass which is being wound, means for traversing the winding-guide outward and inward to deliver the wire or other material in increasing or decreasing flat spirals successively, a series of segmental pressers 35 40 between which and the preceding spiral the winding-guide delivers the wire or other material, and a cam producing a clearance-wave in said series at the winding-guide.

13. In a winding machine, in combination, a winding-guide, means for producing relative rotation between the mass which is being wound and the said winding-guide, means for traversing the winding-guide outward and inward to deliver the wire or other 45 50 material in increasing and decreasing spirals successively, and presser-means having a continuous surface between which and the preceding spiral the winding-guide delivers the wire or other material, said surface 55 forming in a progressive wave to the winding-guide and immediately resuming working position.

14. In a winding machine, in combination, a non-rotating winding-guide, means for rotating the mass which is being wound, means for traversing the winding-guide outward and inward to deliver the wire or other material in increasing and decreasing flat spirals successively, and presser-means having 60 65 a continuous surface between which and the

preceding spiral the winding-guide delivers the wire or other material, said surface conforming in a progressive wave to the winding-guide and immediately resuming working position.

70

15. In a winding machine, in combination, a winding-guide, means for producing relative rotation between the mass which is being wound and the said winding-guide, means for traversing the winding-guide outward and inward to deliver the wire or other material in increasing and decreasing spirals successively, and presser-means including a series of segmental pressers and a continuous flexible surface between which latter and the preceding spiral the winding-guide delivers the wire or other material, said pressers and flexible surface conforming in a progressive wave to the winding-guide.

75

16. In a winding machine, in combination, a non-rotating winding-guide, means for rotating the mass which is being wound, means for traversing the winding-guide outward and inward to deliver the wire or other material in increasing and decreasing flat spirals successively, and presser-means including a series of segmental pressers and a continuous flexible surface between which latter and the preceding spiral the winding-guide delivers the wire or other material, 80 85 said pressers and flexible surface receding in a progressive wave at the winding-guide.

90

17. In a winding machine, in combination, a revoluble cylinder, a winding-arbor revolving in unison with said cylinder and adapted to move axially thereof as the wound coil grows in length, a winding-guide moving outward and inward to deliver the wire or other material in increasing and decreasing spirals successively, and presser-means comprising a continuous flexible surface making contact with the adjacent convolutions, a circular series of presser-segments actuating said flexible surface to hold 100 105 said convolutions against the preceding spiral, and means producing a progressive clearance-wave in said presser-segments at the winding-guide.

110

18. In a winding machine, in combination, a revoluble cylinder, a winding arbor revolving in unison with said cylinder and adapted to move axially thereof as the wound coil grows in length, a winding-guide moving outward and inward to deliver the wire or other material in increasing and decreasing 115 120 spirals successively, and presser-means revolving with the said cylinder, between which and the preceding spiral the winding-guide delivers the wire or other material in forming the convolutions of the new spiral, 125 said presser-means forming a progressive clearance-wave at the winding-guide.

19. In a winding machine, in combination, a revoluble cylinder in unison with which the mass being wound revolves, a winding- 130

- guide moving outward and inward to deliver the wire or other material in increasing and decreasing coils successively, and presser-means revolving with the said cylinder, between which and the preceding spiral the winding-guide delivers the wire or other material in forming the convolutions of the new spiral, said presser-means forming a progressive clearance-wave at the winding-guide.
20. In a winding machine, in combination, a revoluble cylinder having longitudinal grooves, a winding-arbor revolving in unison with said cylinder and adapted to move axially thereof as the wound coil grows in length, a winding-guide moving outward and inward to deliver the wire or other material in increasing and decreasing spirals successively, and presser-means comprising a circular series of presser-segments mounted in said longitudinal grooves and acting to hold the last-wound convolutions against the preceding spiral, and means producing a progressive clearance-wave in said presser-segments at the winding-guide.
21. In a winding machine, in combination, a revoluble cylinder, a winding arbor revolving in unison with said cylinder and adapted to move axially thereof as the wound coil grows in length, a winding-guide moving outward and inward to deliver the wire or other material in increasing and decreasing spirals successively, and presser-means including a circular series of presser-segments carried by said cylinder and moving longitudinally thereon to form a progressive clearance-wave at the winding-guide.
22. In a winding machine, in combination, a revoluble cylinder, a winding-arbor revolving in unison with said cylinder and adapted to move axially thereof as the wound coil grows in length, a winding-guide moving outward and inward to deliver the wire or other material in increasing and decreasing spirals successively, and presser-means comprising a circular series of presser-segments revolving with the cylinder, holding in place against the preceding spiral the portion of wire or other material just delivered by the guide, and a cam producing a progressive clearance-wave in said presser-segments at the winding-guide.
23. In a winding machine, in combination, a revoluble cylinder, a winding-arbor revolving in unison with said cylinder and adapted to move axially thereof as the wound coil

grows in length, a non-rotating winding-guide moving outward and inward to deliver the wire or other material in increasing and decreasing spirals successively, presser-means revolving with the said cylinder between which and the preceding spiral the winding-guide delivers the wire or other material in forming the convolutions of the new spiral, said presser-means forming a progressive clearance-wave at the winding-guide.

24. In a winding machine, in combination, a revoluble cylinder, a winding-arbor revolving in unison with said cylinder and adapted to move axially thereof as the wound coil grows in length, a non-rotating winding-guide moving outward and inward to deliver the wire or other material in increasing and decreasing spirals successively, and presser-means including a circular series of presser-segments carried by said cylinder and moving longitudinally thereon to form a progressive clearance-wave at the winding-guide.

25. In a winding machine, in combination, a revoluble cylinder, a winding-arbor revolving in unison with said cylinder and adapted to move axially thereof as the wound coil grows in length, a non-rotating winding-guide moving outward and inward to deliver the wire or other material in increasing and decreasing spirals successively, and presser-means comprising a circular series of presser-segments revolving with the cylinder, holding the new convolutions against the preceding spiral, and a cam producing a progressive clearance-wave in said presser-segments at the winding-guide.

26. In a machine for winding in spiral layers, one against another, in combination, means for applying a coating to the material on its way to be wound, a presser which acts in axial direction against one end of the mass being wound, and which progressively conforms to the winding guide and holds in place the portion of material that has just been laid by the said guide, and a winding guide which traverses outward and inward between the presser and the said end of the wound mass to lay the material in increasing and decreasing layers successively.

In testimony whereof I affix my signature in presence of two witnesses.

CULLEN B. SNELL.
